ICE CREAM FLAVOR DISPLAY RACK OR THE LIKE

Lyons I. Jossem, Rochester, N. Y.

Application July 12, 1956, Serial No. 42,235

Term of patent 7 years

(Cl. D80—10)

Fig. 1 is a front view of an ice cream flavor display rack or the like, showing my new design;

Fig. 2 is a fragmentary section on an enlarged scale on the line 2—2 of Fig. 1 looking in the direction of the arrows;

Fig. 3 is a fragmentary section on the same scale as Fig. 2 taken on the line 3—3 of Fig. 1 looking in the direction of the arrows; and

Fig. 4 is a section on the same scale as Fig. 1 taken on the line 4—4 of Fig. 1 and looking in the direction of the arrows.

I claim:

The ornamental design for an ice cream flavor display rack or the like, as shown.
